DEVICE FOR COMPOUNDING MIXED DRINKS

Guy P. Le Moine, Fort Myers, Fla.

Application August 26, 1946, Serial No. 693,125

3 Claims. (Cl. 73—428)

1

This invention relates to a device or unit adapted to be used in the compounding of mixed drinks, especially cocktails, and has for its primary object to provide a device by means of which anyone, without prior training or practice, may mix any one of a wide variety or types of mixed drinks with the accuracy of a skilled and trained bartender.

More particularly, it is an object of the invention to provide a unit having unitary means for supporting a plurality of containers and a plurality of recipe strips in predetermined relationship to one another and whereby by following the directions on the strips and employing portions of the strips as a measuring guide, any one of a wide variety of mixed drinks may be accurately compounded.

Still a further object of the invention is to provide a unit of the aforescribed character by means of which the recipe strips may be quickly adjusted for exposing the desired strip containing the indicia and graduations required in the compounding of a particular drink selected.

Still a further object of the invention is to provide a device or unit for the aforescribed purposes of extremely simple construction which is capable of being economically manufactured and sold, which is extremely durable and very efficient for its intended purposes.

Various other objects and advantages of the invention will hereinafter become more fully apparent from the following description of the drawings, illustrating a preferred embodiment thereof, and wherein:

Figure 1 is a front elevational view of the device;

Figure 2 is a side elevational view, partly in vertical section, looking toward the right-hand end of Figure 1;

Figure 3 is a horizontal sectional view taken substantially along a plane as indicated by the line 3—3 of Figure 1;

Figure 4 is an enlarged transverse vertical sectional view taken substantially along a plane as indicated by the line 4—4 of Figure 3;

Figure 5 is a horizontal sectional view taken substantially along a plane as indicated by the line 5—5 of Figure 4; and

Figure 6 is a plan view of one of the recipe strips or cards.

Referring more specifically to the drawings, the drink mixing device or unit in its entirety is designated generally 7 and includes a substantially flat base 8 which is adapted to rest upon any suitable supporting surface, such as a table

2

and which is provided, intermediate of its ends, with an opening 9 having an enlargement 10 at the under side of the base 8, as seen in Figure 4.

The unit 7 also includes a compound rack 11 which is formed from a single strand of wire the intermediate portion of which is bent to provide a relatively small loop 12 forming an eye to receive a screw 13 which extends downwardly therethrough and through the opening 9 and on the shank end of which is threaded a nut 14 which is contained within the recess or enlargement 10. The fastenings 13, 14 provides the sole means for detachably but securely fastening the rack 11 to the base 8.

As best illustrated in Figure 3, one terminal of the wire strand is bent to form an arcuate, open loop 15 and said strand, between the eye 12 and said loop 15 is provided with a smaller, substantially circular loop 16. The loops 15 and 16 are disposed above and adjacent opposite ends of the base 8 and in longitudinal alignment and are connected by a substantially straight strand portion 17 which is provided intermediate of its ends, with a small loop forming an eye 18 which is arranged in substantially a plane parallel to the plane of the base 8. The bar 17 merges with one end of the loop 16 and the other end thereof, as best seen in Figure 1, terminates in a down turned strand portion 19 which in turn merges with a strand portion 20. The strand portion 20 is disposed substantially at a right angle to the strand portion 19 and rests substantially flush against the upper surface of the base 8 and has one end, as previously stated, merging with the upright portion 19 and an opposite curved end which merges with one end of the loop forming the eye 12. The other end of the loop forming the eye 12 merges with a strand portion 21 which likewise rests on the upper side of the base 8 and which terminates in an upwardly extending strand portion forming a standard 22 which extends upwardly through the eye 18 and to a point substantially above the loops 15 and 16, as best illustrated in Figure 2.

The upper end of the standard 22 terminates in a turned back portion 23 which merges with one end of a bar portion 24. The bar portion 24 is disposed substantially parallel to the plane of the base 8 and substantially at a right angle to the axis of the standard 22 and terminates at its outer, forward end in one end of a substantially semi-circular arch portion 25 which is disposed substantially transverse of the base 8. The rear end of the arch 25 converges with a rod portion 26 which extends inwardly and toward the stand-

ard 22 and which is disposed substantially in alignment with the rod portion 24. The rod portion 26 terminates in a relatively short up-turned inner end 27 which forms the other terminal of the wire strand forming the rack 11 and the upper end of which is disposed substantially at the level of the upper end of the standard 22 and in spaced relationship thereto, as best illustrated in Figure 2.

The mixing device 1 also includes a plurality of elongated cards or strips 28 which are relatively narrow and each of which is provided with an opening 29 adjacent the upper end thereof. The strips 28 may be formed of any suitable material which is relatively rigid and yet relatively thin and each of the strips 28 has suitably inscribed on one side thereof indicia necessary to be followed in the correct compounding of a particular drink. The strips 28 are applied to the rack 11 by passing the openings thereof over the up-turned end 27, along the rod portion 26, over the arch 25 and onto the rod portion 24 so that the side thereof containing the indicia constituting the recipe is disposed to face outwardly, as illustrated in Figure 1. Each of the strips 28 has indicia adjacent its upper end and beneath its opening 29, as seen in Figure 1, indicating the name of the drink, the recipe for which is contained thereon, and said strips 28 are preferably arranged in alphabetical order so that the strip 28 containing the desired drink can be readily located and all strips 28 located in front thereof can be moved over the arch 25 and onto the bar portion 26, as illustrated in Figure 2, so that the recipe for the desired drink will be disposed in an exposed position, as illustrated in Figure 1.

If it is desired to compound a dry martini, the strips are moved, as just previously described to expose the strip 28 containing the recipe for the dry martini, and it will be noted that this strip 28, adjacent its lower end, is provided with two transverse lines which are longitudinally spaced. Beneath the lower line 30 is the indicia "Dry Gin" and beneath the upper line 31 is the indicia "French Vermouth." Between the upper line 31 and the upper part of the strip 28 where the name or title "Martini (dry)" is contained, the space therebetween contains the directions for compounding a dry martini including, placing a dash of bitters in the glass, putting cracked ice in the shaker and pouring the contents of the small glass into the shaker, shaking and straining the liquid into a three ounce cocktail glass and adding an olive.

As best illustrated in Figure 1, the loop or glass rack 15 contains a relatively large mixing glass 32 and the smaller loop or glass rack 16 contains a smaller mixing glass 33. The glasses 32 and 33 rest on the base 8 and when so disposed are snugly engaged by the glass racks 15 and 16.

For example if it is desired to compound a dry martini for one person the glass 33 is filled up to the level of the line 30 with dry gin and then filled up to the level of the line 31 with French vermouth after which these ingredients are poured into a cocktail shaker with a dash of bitters and the ice added, as previously described. If it is desired to mix two dry martinis, the gin is poured into the larger glass 32 up to the level of the line 30 and French vermouth is thereafter poured into the mixing glass 32 up to the level of the line 31 and the previously described operation repeated. For mixing three cocktails, both

glasses 32 and 33 are filled, as previously described and to the levels mentioned.

It will thus be readily apparent that any person without previous knowledge of drink mixing may accurately and efficiently mix any drink and without waste and for any desired number of persons with the technique of an experienced bartender.

Various modifications and changes are contemplated and may obviously be resorted to, without departing from the spirit and scope of the invention as hereinafter defined by the appended claims.

I claim:

1. In a drink mixing device, a base, a rack secured thereto and disposed thereabove, said rack being provided with a container holder disposed above and parallel to the base and adapted to support a transparent mixing container in a fixed position on the base, a card holding portion forming a part of the rack adapted to support a recipe card in predetermined spaced relationship to the mixing container and externally thereof, said card bearing indicia on one side thereof including graduations and instructions for the compounding of a particular drink, and said card holding portion being disposed at a predetermined level above the container holder and base and substantially parallel to the plane of each to support the card with the graduations thereof at a predetermined level relatively to the mixing container bottom, said card holding portion including spaced rod portions disposed substantially parallel to the base and each of which is adapted to support a plurality of the indicia bearing cards, and an arcuate portion connecting said rod portions and by which the cards are movable from one rod portion to the other.

2. In a drink mixing device, a base, a rack secured thereto and disposed thereabove, said rack being provided with a container holder disposed above and parallel to the base and adapted to support a transparent mixing container in a fixed position on the base, a card holding portion forming a part of the rack adapted to support a recipe card in predetermined spaced relationship to the mixing container and externally thereof, said card bearing indicia on one side thereof including graduations and instructions for the compounding of a particular drink, and said card holding portion being disposed at a predetermined level above the container holder and base and substantially parallel to the plane of each to support the card with the graduations thereof at a predetermined level relatively to the mixing container bottom, said card holding portion including spaced rod portions disposed substantially parallel to the base and each of which is adapted to support a plurality of the indicia bearing cards, and an arcuate portion connecting said rod portions and by which the cards are movable from one rod portion to the other, one of said rod portions terminating at its inner end in an up-turned terminal portion over which said cards may be moved for applying them to or removing them from the card rack.

3. In a drink mixing device, a base, a rack secured thereto and disposed thereabove, said rack being provided with a container holder disposed above and parallel to the base and adapted to support a transparent mixing container in a fixed position on the base, a card holding portion forming a part of the rack adapted to support a recipe card in predetermined spaced relationship to the mixing container and externally thereof, said card bearing indicia on one side thereof including

graduations and instructions for the compounding of a particular drink, and said card holding portion being disposed at a predetermined level above the container holder and base and substantially parallel to the plane of each to support the card with the graduations thereof at a predetermined level relatively to the mixing container bottom, said card holding portion and container holder being integrally formed, said card holding portion including spaced rod portions disposed substantially parallel to the base and each of which is adapted to support a plurality of the indicia bearing cards, and an arcuate portion connecting said rod portions and by which the cards are movable from one rod portion to the other.

15 GUY P. LE MOYNE.
